RADIATOR GUARD AND METHOD OF
MAKING SAME

George E. Whitlock, Toledo, Ohio, assignor to
The City Auto Stamping Company, Toledo,
Ohio, a corporation of Ohio

Application March 27, 1933. Serial No. 663,087

2 Claims. (Cl. 29—160)

The invention relates to guards or grills such as are used for the protection of motor vehicle radiators and the invention consists in the novel construction and method of forming the same 5 as hereinafter set forth.

In the drawing:

Fig. 1 is an elevation of the pressed blank before the crimping operation;

Fig. 2 is a similar view of the crimped blank;

Fig. 3 is an end elevation.

It is the primary object to obtain a guard comprising a series of parallel bars each of U-shaped cross section and of a depth approximating the spacing between adjacent bars, the said structure 10 being formed by the pressing of a single sheet metal blank. Inasmuch as each bar is provided with a pair of flanges and as the depth of each flange approximately equals the space between adjacent bars, it is obvious that there would be 15 insufficient metal in a blank, the original width of which was equal to the width of the pressed structure. On the other hand, if the blank is of sufficient width to provide metal for the U-shaped bars, then the spacing between said bars must 20 be at least twice the depth thereof. Also the unpressed end portions of the blank will hold the bars in this spaced relation. I have, however, overcome this difficulty by crimping the end portions of the blank intermediate adjacent bars

which takes up the extra metal and produces the desired spacing.

As shown in the drawing, A is the sheet blank which is of an original width sufficient to form all of a series of bars B, each of a U-shaped cross section and of the desired depth. The blank is then pressed to form these bars with an integral connecting ear portion C at opposite ends of the bars. These portions C are then crimped to form return bends D of such depth as to contract the 65 distance between adjacent bars B to the required dimension.

What I claim as my invention is:

1. The method of forming guards or grills comprising the pressing of a sheet metal blank to 70 form a series of parallel bars of U-shaped cross section and of a predetermined depth with an integral connecting portion at the ends of said bars, and in crimping said connecting portion intermediate the bars to reduce the width thereof 75 and to obtain the desired spacing between parts.

2. A guard or grill comprising an integral sheet metal blank having a series of parallel bars, each of a U-shaped cross section and with integral 80 end portions connecting said bars, said end portions being crimped intermediate said bars to contract the width thereof.

GEORGE E. WHITLOCK.
